UNITED STATES PATENT OFFICE.

GEORGE WILLIAM JONES, OF OWENS, FLORIDA.

TRUNK-HARNESS.

No. 818,251.

Specification of Letters Patent.

Patented April 17, 1906.

Application filed August 25, 1905. Serial No. 275,822.

To all whom it may concern:

Be it known that I, GEORGE WILLIAM JONES, a citizen of the United States, residing at Owens, in the county of De Soto and State of Florida, have invented a new and useful Trunk-Harness, of which the following is a specification.

The present invention is an improved trunk-harness capable of being readily fitted to a trunk so as to brace the same and fasten the lid independently of the usual lock therefor. It is also proposed to enable the convenient application of the harness to a trunk or other package, to facilitate the adjustment of the device and tightening thereof, and to afford protection for the corners of the trunk in a novel and highly efficient manner.

With these and other objects in view the present invention consists in the combination and arrangement of parts as will be hereinafter more fully described, shown in the accompanying drawing, and particularly pointed out in the appended claims, it being understood that changes in the form, proportion, size, and minor details may be made within the scope of the claims without departing from the spirit or sacrificing any of the advantages of the invention.

In the drawing there has been shown a perspective view of a trunk-harness embodying the features of the present invention with the outline of a trunk indicated in dotted lines.

The present device includes a set of eight corner-buffers 1, of rubber or other suitable material, each buffer being provided with a socket 2 to receive one of the corners of the trunk, crate, or other package. Intersecting upright and horizontal guideways 3 and 4 are formed through each buffer for the reception of a flexible connection 5, preferably a rope or cord, which will slide freely through the guideways. While the guideways have been shown in the nature of openings, they may be formed by grooves, as will be readily understood without illustration thereof. There is one cord for each set of four diagonally-opposite buffers, the middle portion of the cord passing across the bottom of the trunk and the ends of the cord extending diagonally across the top of the trunk, one end of the cord being provided with a buckle 6 and the other end having a strap or other flat tongue 7 secured thereto for convenience in engagement with the buckle. It will now be understood that two cords cross one another

diagonally at the bottom and the top of the trunk and extend vertically between the respective pairs of upper and lower buffers, so that when the cords are tightened by means of the tongues 7 and buckles 6 the buffers 6c will be drawn snugly upon the corners of the trunk and the latter effectually braced by the cords.

To obtain a greater tightening of the cords than can be accomplished by means of 65 tongues and buckles, there are provided duplicate tightening devices, one for the top and the other for the bottom of the harness. Each of these tightening devices includes opposite cross-bars 8, located adjacent the respective 70 ends of the trunk and provided with terminal perforations 9 for the loose reception of the respective cords, there being an adjustable connection between the cross-bars for drawing the same toward one another. This 75 adjustable connection preferably consists of a pair of straps 10, connected to one of the cross-bars adjacent its respective ends and provided at their outer ends with buckles 11, there being other straps 12 connected to the 80 opposite cross-bar and engaged with the respective buckles. By tightening the connections between the cross-bars the latter will be drawn toward one another and the diagonally-crossed cords thereby spread or separated, which places a greater tension thereon than can be accomplished by the buckles and tongues 6 and 7.

From the foregoing description it will be seen that the device of the present invention 90 is very simple and at the same time efficient for the purpose designed. It may be readily applied to a trunk or the like and when tightened braces the trunk in a strong and durable manner and at the same time protects the 95 corners thereof by means of the buffers 1. Should the trunk-lock and other fastenings or any other portion of the trunk become broken, the harness will hold the trunk together in an effective manner, thereby preventing loss of 100 the contents of the trunk.

Having thus described the invention, what is claimed is—

1. A trunk-harness comprising a set of corner-buffers having guideways, and a pair of 105 cords loosely engaging the guideways of the respective diagonally opposite buffers, the ends of each cord being provided with adjustable connections.

2. A trunk-harness comprising a set of cor- 110

ner-buffers provided with guideways, a pair of cords loosely engaging the guideways of the respective diagonally opposite buffers and crossed at the top and bottom of the device, 5 one end of each cord being provided with a buckle and the other end of the cord being adapted for engagement with the buckle.

3. A trunk-harness comprising corner-buffers, crossed cords connecting the diagonally opposite buffers, and tightening means engaging the cords for spreading the same to place a tension thereon.

4. A trunk-harness comprising corner-buffers, crossed cords connecting the buffers, opposite cross-bars slidably engaging the cords, and means for moving the cross-bars upon the cords to spread the same and thereby place a tension thereon.

5. A trunk-harness comprising corner-buffers, diagonally-crossed cords connecting the buffers, cross-bars slidably engaging the cords, and an adjustable connection between the cross-bars to move the same upon the

cords and spread the latter to place a tension thereon. 25

6. In a trunk-harness, the combination with a set of corner-buffers having guideways, of a pair of cords loosely engaging the guideways of the respective diagonally opposite buffers, said cords being crossed at the top and bottom of the device, an adjustable connection between the ends of each cord, cross-bars loosely pierced by the crossed portions of the respective cords, corresponding straps connected to the cross-bars, and an 30 adjustable connection between the straps for moving the cross-bars upon the cords to spread and place a tension upon the latter.

In testimony that I claim the foregoing as my own I have hereto affixed my signature 40 in the presence of two witnesses.

GEORGE WILLIAM JONES.
